UNITED STATES PATENT OFFICE.

EDMUND H. LUNKEN, OF CINCINNATI, OHIO, ASSIGNOR TO THE LUNKENHEIMER COMPANY, OF CINCINNATI, OHIO, A CORPORATION OF OHIO.

DESIGN FOR A NEEDLE-VALVE SNAP-BUTTON.

49,067.

Specification for Design.

Patented May 16, 1916.

Application filed February 24, 1916. Serial No. 80,302. Term of patent 14 years.

To all whom it may concern:

Be it known that I, EDMUND H. LUNKEN, a citizen of the United States, and a resident of the city of Cincinnati, in the county of Hamilton and State of Ohio, have invented a new, original, and ornamental Design for Needle-Valve Snap-Buttons, of which the following is a specification, reference being had to the accompanying drawing, forming part thereof.

In the drawing, the figure is a perspective view of the snap button showing my new design.

I claim:

The ornamental design for a needle valve snap button, as shown.

EDMUND H. LUNKEN.

Witnesses:

LORENZ L. LEMPER,
K. SMITH.
